UNITED STATES PATENT OFFICE.

EUGENE M. BEALS, OF PITTSBURGH, PENNSYLVANIA, ASSIGNOR TO UNIVERSAL
VISIBLE CALCULATOR COMPANY, OF PITTSBURGH, PENNSYLVANIA, A CORPO-
RATION OF PENNSYLVANIA.

CALCULATOR DEVICE.

Application filed May 28, 1921. Serial No. 473,258.

To all whom it may concern:

Be it known that I, EUGENE M. BEALS, a citizen of the United States, residing at Pittsburgh, in the county of Allegheny and 5 State of Pennsylvania, have invented a new and useful Improvement in Calculator Devices, of which the following is a full, clear, and exact description.

My invention relates to a calculator device and is useful in any connection where it 10 is desirable to have ready means of ascertaining the total or product of whole numbers or fractions.

An object of my invention is such a device 15 which is simple in construction and easy to use.

Another object of my invention is such a device which is compact in form, at the same time having a large range.

20 A further object of my invention is such a device which is reversible so that both sides of the information cards together with both sides of the container may be used to get the desired results.

25 My invention will be better understood upon the reading of the following description taken in connection with the accompanying drawings showing one embodiment of my invention, and in which:

30 Figure 1 is a front elevation;

Figure 2 is a section taken on the line II—II of Figure 1;

Figure 3 is a section taken on the line III—III of Figure 1;

35 Figure 4 shows an enlarged detail view; and

Figure 5 shows one of the cards in place with one form of information thereon.

Referring to the drawings, the device comprises a stand or base 1 and a container 2. The container is secured to the base by a member 3 having flanges 4 and 5 thereon which pass upwardly around the container 2 and are fastened thereto by rivets 6. The 45 member 3 is secured to the base 1 by a bolt 7 with a nut 8 thereon.

The container 2 comprises a boxlike member having an upper side 9 and a lower side 10, a front side 11, and rear side 12. The 50 container 2 is provided with partitions 13, 14, 15, and 16, thus dividing the interior of the container into compartments 17. In the

illustration shown, there are five of the compartments 17, but it is to be understood that any number of compartments desired may be 55 provided. Placed in the compartments 17 are cards 18 bearing suitable information. The compartments 17 are laterally offset with respect to each other, so that a rectangular portion of the dividing walls is exposed at each end of the device, the rectangular portions extending in stepped relationship. These exposed portions of the partitions or dividing walls are recessed, as shown at 19, and an index is placed on the recessed 60 portion. The index is of a thickness substantially equal to the recess, so that when the index member is applied the surface is substantially flush.

The information cards 18 are placed in 70 the compartments 17 and are of such size as to occupy the compartment without extending outwardly from either side. Each of the cards is provided with a tab 20 at each side, the width of the card being such that both 75 tabs are visible when the card is in position in the compartment. The tabs 20 have a peculiar shape so that when the card is in position the tabs rest against each side of the compartment, as shown in Figure 5, so as to 80 prevent the card from sliding out of the container.

The container 2 is rotatably mounted on the base 1 so that either side may be used and the container rotated to bring the other 85 side into useable position.

The base 1 is of such formation that the device normally stands at a slight angle to the vertical, as shown in Figure 2, the front of the device being the side 11. This angular position of the container 2 renders the device more convenient for use.

The compartments 17 may be described as of substantially equal area and as laterally offset with respect to each other, thus giving 95 the peculiar shaped container, as best shown in Figure 3.

In operation, referring to Figure 1, the index 25 bears an indication of the fractional part of the unit of time, such as $\frac{1}{4}$, $\frac{1}{2}$, $\frac{3}{4}$, and "rate" per unit of time, usually per hour. The card 18 bears the numerical indication of the rate per hour, such as .20, and the calculated values for each fraction or

multiple of the time unit at that particular rate, so that when the card 18 is withdrawn from its compartment to the position shown in Figure 1, the correct calculated total may be read off the card 18 at a glance in conjunction with the index 25 which is provided with fractions and multiples of the time unit. In Figure 1, this index 25 is provided with fractions $\frac{1}{4}$, $\frac{1}{2}$, and $\frac{3}{4}$ of an hour, 1 hour, and from 101 to 125 hours, inclusive, and the card 18 bears the calculated total for each of those units at the rate given on the card 18.

It will be noted that the index 21 has the same fractions and hours from 1 to 25; the index 22 has the same fractions and the hours 26 to 50; the index 23 the same fractions and hours from 51 to 75; and the index 24 the same fractions and hours 76 to 100. The indexes 21 to 25, inclusive, carry the time units from 1 to 125, there being 25 of such units on each card; and each of the cards is provided with fractional indications $\frac{1}{4}$ to $\frac{3}{4}$.

It will be understood, of course, that the indexes may bear any fractions or multiples of any desired unit, and the cards 18 having information for cooperation with the index, may likewise be changed to carry the calculated totals for each of the units at the desired rate. Furthermore, the range of fractions or multiples of the unit may vary to cover any desired condition, depending upon the particular case for which the calculator is designed.

This range may be extended by continuing the same unit and rate on the index portion at the other end of the device; that is to say, the index portion 26, indicated in dotted lines in Figure 1, may be provided with fractional indications and the hour indications of 126 to 150; the index 27 the same fractional indications and the hours of 151 to 175, and so on, to cover any desired range. The information for cooperation with the indexes 26 and 27 and any others that may be desired, is printed or otherwise placed on the reverse side of the cards 18 so that by the particular arrangement of the compartments with respect to each other, that is to say, by the lateral offsetting and stepped relationship, the information is not only made visible, but both sides of the cards and of the container may be used without removing any of the cards from their compartments, it being necessary in each case to do nothing more than slide the card so as to bring it out sufficiently far to exhibit the calculated totals at the particular rate desired.

Any suitable information may be placed at the top of the index strips to indicate the range covered by that strip, such as for instance the number of hours or other units contained on that strip.

Any suitable information may also be

placed on the tabs 20, such as the range covered by the card to which the tab is attached, as indicated for instance in Figure 5.

It may be mentioned also that each of the cards 18 is provided with a plurality of columns of figures each calculated at a different rate, these columns being parallel to each other and occupying substantially the space shown on the card 18 in Figure 1, so that each card 18 may be provided with calculated totals based on a plurality of rates, each one of the columns containing information for cooperation with the particular index ranging from 1 to 250 in a device such as that shown in Figure 1.

From the foregoing, it will be evident that my invention has many advantages over any device heretofore known, in that the cards used may bear information on both sides; the container is simple in construction; it is reversible; it is not necessary to remove the cards in order to use both sides; the indexes are fixed; and the information on the indexes and on the cards is arranged vertically so that it is readily observable, and the results or totals are apparent from the cards and require no mental calculations whatever.

While I have described my invention in detail and illustrated one particular form of device embodying the same, I desire it to be understood that I am not to be limited to the particular detail form indicated and described, as many detail changes may be made without departing from the spirit of my invention.

I claim:

1. A calculator device comprising a container having a plurality of compartments laterally offset and in rearwardly stepped relation with respect to each other, substantially as described.

2. A calculator device comprising a container having a plurality of compartments laterally offset and in rearwardly stepped relation with respect to each other, and an index on said offset portion, substantially as described.

3. A calculator device comprising a container having a plurality of overlapping partitions offset laterally and spaced to form compartments laterally offset with respect to each other, an index on the offset portions of said partitions, and cards in said compartments having information for cooperation with said indexes, substantially as described.

4. A calculator device comprising a container having a plurality of compartments of substantially equal length relatively offset laterally and rearwardly, substantially as described.

5. A calculator device comprising a container having a plurality of overlapping compartments of substantially equal length

- and width relatively offset laterally at two opposite sides, and indicia-carrying members having dimensions substantially equal to the dimensions of said compartments whereby they may be normally concealed therein but are adapted to cooperate with the offset portions at either side, substantially as described.
6. A calculator device comprising a container having a plurality of overlapping, separate compartments of substantially equal length relatively offset, and an index on each offset portion, substantially as described.
7. A calculator device comprising a container having a plurality of overlapping, separate compartments of substantially equal length relatively offset, an index on each offset portion, and cards in said compartments containing information for cooperation with said indexes, substantially as described.
8. A calculator device comprising a container having a front and rear face and a plurality of compartments of substantially equal length relatively offset laterally at two opposite sides and stepped rearwardly relative to each face, an index on each offset portion, and cards in said compartments containing information for cooperation with said indexes, substantially as described.
9. A calculator device comprising a rotatable container having a plurality of overlapping, separate compartments of substantially equal length relatively offset laterally at two opposite sides, an index on each offset portion, and cards in said compartments containing information for cooperation with said indexes, said cards having dimensions substantially equal to the dimensions of said compartments, substantially as described.
10. In a calculator, a plurality of partition members each having at least one edge portion thereof constructed to form a recess, and an index held in each of said recesses, substantially as described.
11. In a calculator, a plurality of partition members each having at least one edge portion thereof constructed to form a recess, an index held in each of said recesses, and means for holding said partitions in laterally offset and rearwardly spaced relationship, substantially as described.

In testimony whereof I have hereunto set my hand.

EUGENE M. BEALS.
